JOHN B. MOORE, OF RIVERHEAD, NEW YORK, ASSIGNOR TO RADIO CORPORATION OF AMERICA, A CORPORATION OF DELAWARE

VOLUME CONTROL COMBINING SYSTEM

Application filed November 16, 1928. Serial No. 319,767.

This invention relates to diversity reception, and more particularly to volume control therefor.

Communication on very high frequency carriers is economical of power but is handicapped by prevalence of fading. Inasmuch as fading may differ very widely at geographically spaced points, or in different planes of polarization, it has been proposed to reduce fading by diversity systems of reception, which employ a number of antennas having different fading characteristics, the energies from which are finally combined together. The volume of the received energy is apt to vary between the extremes of almost complete fading at all of the antennas to no fading at any of the antennas. To overcome this it has been proposed to equip the receivers for the antennas each with a volume control, but this, in addition to the requirement of a considerable number of volume controls, suffers from two great disadvantages. One applies to code or speech-simulating signals, and is that the amplifiers of those antennas at which fading is prevalent are given increased gain, in consequence of which the noise level of the combined energy is greatly increased. The other applies more particularly to speech-simulating signals, and is that the amplifier of an antenna at which the carrier is fading, while the sidebands are not, is given increased gain, in consequence of which the distortion resulting from the beat between the sidebands is greatly increased.

To overcome the foregoing difficulties is the primary object of my invention, which I attain by simultaneously controlling the gain in the amplifiers of the separately collected energies all in response to the volume of the combined energy. In this manner the amplifiers experience equal changes in gain, so that the energy from an antenna at which no fading is present retains its magnitude relative to the small energy at antennas located at fading points, and dominates such energy, thereby improving the quality of the combined energy.

When dealing with energies of sufficiently high frequency so that the phases of the received energies at the different antennas

fluctuate relative to one another, even though of like constant frequency, it is not feasible to combine the received energies directly together, and in such case my invention includes separately detecting the amplified energies, combining the detected energies so that the combination is substantially independent of the relative radio frequency phase at the different antennas, and controlling the gain in the step of amplification of all of the collected energies in response to the volume of the combined detected energy, as well as utilizing the combined energy to obtain the desired signal.

My invention is more completely described in the following specification, which is accompanied by a drawing the single figure of which is a wiring diagram for a preferred form of my invention.

Referring to that figure there are a plurality of diversity antennas 2, 4 and 6, which are either geographically spaced, or located in different planes of polarization, or in any other manner given different fading characteristics. These antennas are coupled by transmission lines 8, 10 and 12 to a plurality of radio frequency amplifiers 14, 16 and 18. The output from each of these amplifiers is coupled to means to heterodyne the radio frequency energy to energy of intermediate frequency, indicated by the rectangles 20, 22 and 24. These means may comprise a source of locally generated energy of relatively high frequency and a separate heterodyne detector, or a single autodyne circuit in which the electron emission tube which functions as an oscillator also acts as a detector for combining the received and locally generated energies. The resulting energy of intermediate frequency is amplified in intermediate frequency amplifiers 26, 28 and 30. The amplified output is fed to detector tubes 32, 34 and 36, across the output circuit of each of which there is connected one or more low pass filter sections 38, 40 and 42, for by-passing the radio frequency components of the rectified energies.

The signal components of the rectified energies are fed through leads 44, 46 and 48 to a common lead 50, in series with which a source

of direct anode potential 52 is connected. The circuit from the detector tube anodes to ground is completed through a volume control impedance 54, cooperating with which, by 5 either a parallel or series connection, is a condenser 56, the magnitude of which is properly chosen to give the volume control action the desired time constant. The impedance 54 is desirably a resistance, and is not necessarily but preferably is connected, as shown, 10 between the source of anode potential 52 and ground, in order to keep it at a relatively low potential. From one terminal of the volume control impedance a lead 58 is connected to 15 branch leads 60, 62 and 64, which are connected to the control electrodes of the vacuum tubes of the amplifiers, in the usual manner. In series with the common lead 58 a source of constant bias potential 66 may be connected 20 to fix the normal bias of the amplifier tubes at the proper value.

To obtain a portion of the combined energy for utilization a coupling impedance 68 is provided in parallel with the volume control 25 circuit. Across some or all of the coupling impedance 68 the input circuit of an amplifier tube 70 is coupled, and if desired, the control electrode of the coupling tube may be biased from a potential source 72, insulated from the 30 coupling impedance 68 by a blocking condenser 74. The output of the amplifier tube 70 may be further amplified in a pushpull amplifier stage 76, the output from which is connected to a line 78 leading to a sound or 35 picture translating device, rebroadcasting station, or other utilization means.

It should be understood that the essentials of the described apparatus are merely a plurality of antennas of different fading characteristics, a plurality of amplifying receivers coupled thereto, and a common volume control responsive to the volume of the combined energy from the receivers for simultaneously controlling the amplification gain in all of 40 the receivers. As a further modification, in order to combine the separately collected energies substantially independently of relative radio frequency phase at the antennas, there may be provided means to separately detect 45 the amplified energies, and means to combine the amplified energies after detection both for volume control and for utilization. The exact number and type of antennas, and mode of giving them different fading characteristics, are not material. The use of means to 50 heterodyne the received energy together with means to amplify the resulting intermediate frequency energy is entirely optional, and when used, the volume control may be applied 55 to either the radio frequency amplifier or the intermediate frequency amplifier alone, as well as to both amplifiers, as shown. The particular form of the volume control circuit, and of the coupling means for the utilization 60 circuit, may be varied widely, for ex-

ample, by connecting the coupling impedance and volume control impedance in series, and the time constant condenser and volume control impedance in parallel, but I believe the arrangement illustrated in the drawing is the 70 most desirable one.

I claim:

1. The method of diversity reception which includes simultaneously making a plurality of separate energy collections of relatively 75 different fading characteristics, separately amplifying the collected energies, separately detecting the amplified energies producing thereby unidirectional undulatory energy, combining the unidirectional energies, controlling the gain in the aforesaid step of amplification of a plurality of the collected energies in response to the volume of the combined unidirectional energy, and translating the combined energy.

2. The method of diversity reception which includes collecting the radiated energy at a plurality of spaced points, separately amplifying the collected energies, separately detecting the amplified energies to obtain 90 undulatory unidirectional energy, combining the detected unidirectional energies, controlling the gain in the aforesaid step of amplification of a plurality of the collected energies in response to the volume of the combined unidirectional energy.

3. The method of diversity reception which includes collecting the radiated energy at a plurality of spaced points, separately amplifying and heterodyning the collected energies to obtain amplified energies of intermediate frequency, separately detecting the amplified energies to obtain unidirectional undulatory energy, combining the detected 105 unidirectional undulatory energies, controlling the gain in the aforesaid step of amplification of each of the collected energies in response to the volume of the combined energy, and utilizing the combined energy for 110 translation.

4. The combination with a diversity receiving system comprising a plurality of antennas of different fading characteristics and a plurality of amplifying receivers coupled thereto, of a common volume control responsive to the volume of the combined unidirectional undulatory energy from the receivers for simultaneously controlling the amplification gain in all of the receivers, in order 115 to reduce the noise level when the signal fades at a receiving point and/or the distortion resulting from the beat between sidebands when the carrier fades at a receiving point and means for translating the combined unidirectional undulatory energies.

5. A diversity receiving system comprising a plurality of antennas of different fading characteristics, a plurality of amplifiers coupled thereto, means to separately detect 130

the amplified energies thereby obtaining unidirectional undulatory energies, means to combine the detected unidirectional undulatory energies, a common volume control responsive to the combined undulatory energy for simultaneously controlling the gain in a plurality of the aforesaid amplifiers, and means to utilize the combined undulatory energy for translation.

6. A diversity receiving system comprising a plurality of spaced antennas, a plurality of amplifiers coupled thereto, means to separately detect the amplified energies to obtain unidirectional undulatory energies, means to combine the detected unidirectional energies, a common volume control responsive to the combined energy for simultaneously controlling the gain in a plurality of the aforesaid amplifiers, and means to translate the combined unidirectional energy.

7. A diversity receiving system comprising a plurality of spaced antennas, a plurality of amplifiers and means to heterodyne the received energy to obtain amplified intermediate frequency energies coupled thereto, means to separately detect the amplified energies to obtain unidirectional undulatory energies, means to combine the detected energies, a common volume control responsive to the combined energy for simultaneously controlling the gain in each of the aforesaid amplifiers, and means to translate the combined unidirectional energy.

8. A diversity receiving system comprising a plurality of spaced antennas, a plurality of amplifiers coupled thereto, a plurality of detector tubes for detecting the amplified energies, a source of anode potential coupled to all of said detector tubes, a volume control impedance connected in series with said source of anode potential, a condenser cooperating with the impedance to establish the time constant of the volume control action, a connection from the volume control impedance to the control electrodes of the tubes of each of the aforesaid amplifiers for so varying the amplification gain therein as will tend to keep the combined energy constant, a coupling impedance arranged in circuit with the volume control impedance to obtain a portion of the combined energy for utilization, an amplifier coupled to the coupling impedance, and a utilization circuit coupled to the amplifier.

9. A diversity receiving system comprising a plurality of spaced antennas, a plurality of amplifiers coupled thereto, means to separately heterodyne the received energies to obtain energies of intermediate frequency, means to separately amplify the intermediate frequency energies, a plurality of detector tubes for detecting the amplified energies, a source of anode potential coupled to all of said detector tubes, a volume control impedance connected in series with said source of anode potential, a condenser cooperating with the

impedance to establish the time constant of the volume control action, a connection from the volume control impedance to the control electrodes of the tubes in each of the aforesaid amplifiers for so varying the amplification gain therein as will tend to keep the combined energy constant, a coupling impedance arranged in circuit with the volume control impedance to obtain a portion of the combined energy for utilization, an amplifier coupled to the coupling impedance, and a utilization circuit coupled to the amplifier.
